UNITED STATES PATENT OFFICE.

WILLIAM A. E. HENRICI, OF BOSTON, MASSACHUSETTS.

ROTARY ENGINE.

SPECIFICATION forming part of Letters Patent No. 772,882, dated October 18, 1904.

Application filed March 27, 1903. Serial No. 149,797. (No model.)

To all whom it may concern:

Be it known that I, WILLIAM A. E. HENRICI, a citizen of the United States, and a resident of Boston, county of Suffolk, State of Massachusetts, have invented an Improvement in 5 Rotary Engines, of which the following description, in connection with the accompanying drawings, is a specification, like characters on the drawings representing like parts.

10 This invention relates to rotary motors or engines wherein the piston travels in an annular chamber, technically termed the "cylinder," the movement of the piston being effected by the admission of the motive fluid 15 into the cylinder behind the piston and between it and an abutment or diaphragm which is moved into and out of operative position in the cylinder, leaving the latter as the piston approaches it and being operatively positioned 20 immediately after the piston has passed beyond it. For relatively low piston speed reciprocatory movement of the abutment has been successful, because of the ample time afforded for the abutment movement; but when 25 high-speed engines of this type are desired the time period for abutment movement assumes such small proportions that the desired operation of the abutment cannot keep pace with the piston speed. Not only this, but the 30 rapid reversal of movement of the abutment gives rise to injurious strains and vibration in the apparatus, a most serious objection in an engine of even very moderate size and power and increasing to a prohibitive degree with 35 increased engine weight and power.

My present invention has for one of its objects the production of a novel rotary engine or motor as a whole of compact and simple construction and relatively light weight capable of running at a high rate of speed with a minimum of jar or vibration and possessing a very high efficiency.

Another object of my invention is the production of a novel and efficient abutment or diaphragm which is given a positive intermittent rotary movement, permitting a high piston speed and an absolutely accurate cooperation with and movement relative to the piston.

50 Another object of my invention is the pro-

duction of strong, durable, and efficient means for imparting to the abutment movement of the character stated, the abutment being securely locked in its operative position during the major portion of the piston-stroke. The 55 abutment is maintained fluid-tight during admission of the motive fluid in a novel and very efficient though simple manner, and at the time the abutment is moved to permit the passage of the piston it is either practically free 60 from or subjected to equalized pressure, so that its movement consumes little power.

These and various other novel features of my invention will be fully described in the subjoined specification and particularly pointed out in the following claims.

I have chosen to show and describe herein my invention as embodied in a compound engine or motor, the motive fluid being used expansively in the high-pressure cylinder and 70 being governed as to its admission thereto by a rotary valve which in this embodiment of my invention is mounted directly upon and operated by the main shaft of the engine. The exhaust passes from the high to the low pressure cylinder, and by a very novel construction thereof the piston traveling in the latter cylinder governs the admission and exhaust thereof. My invention is not restricted to a compound engine or motor, however, for, as 75 will appear, there are many vital features of construction, operation, and arrangement common to either a simple or a compound engine, and a practical embodiment of the invention in the latter type embraces or includes 80 the former.

Various changes or modifications may be made in different features of the apparatus by those skilled in the art without departing from the spirit and scope of my invention.

Figure 1 is a part front elevation and vertical section of a compound rotary engine or motor embodying one practical form of my invention, the sectional portion being taken on the line 1 1, Fig. 2, and showing the high-pressure abutment or diaphragm in operative position, the cylinder-jackets being shown in section to more clearly illustrate other parts of the apparatus. Fig. 2 is a top or plan view of the apparatus shown in Fig. 1, all of the 95 100

parts being in elevation, and the jackets are omitted altogether for clearness of illustration. Fig. 3 is a left-hand end elevation of the engine or motor, showing the low-pressure cylinder and the means for controlling and operating the diaphragm or abutment co-operating therewith, the fly-wheel being omitted. Fig. 3^a is a detail face view of the rotary valve for controlling admission of motive fluid to the high-pressure cylinder. Fig. 4 is a transverse sectional view of the low-pressure cylinder on the line 4 4, Fig. 2, looking toward the right, the piston and the shaft of the abutment being in elevation. Fig. 5 is a similar view of the high-pressure cylinder, its piston and abutment, and some of the adjacent parts on the line 5 5, Fig. 2, looking toward the left, but not taken at the corresponding instant, as the high and low pressure pistons 20 in actual practice are set one hundred and eighty degrees apart on the main shaft. Fig. 6 is an enlarged side elevation of the low-pressure piston and the hub to which it is secured. Fig. 7 is an end view thereof looking 25 toward the left, Fig. 6. Fig. 8 is an enlarged detail, in side elevation, of the high-pressure piston, its hub being broken off. Fig. 9 is a detail on the line 9 9, Fig. 2, looking toward the right, of the means for controlling the 30 movement of and for locking the high-pressure abutment, the time chosen for illustration being just at the instant when the abutment is unlocked and its movement is just about to be effected. Fig. 10 is a similar view 35 of the same means, but taken when the abutment is just at the center of its movement, the speed-accelerating cam being shown in dotted lines in Figs. 9 and 10. Fig. 11 is a face view of the speed-accelerating cam, the 40 view being taken on the line 9 9, Fig. 2, but looking toward the left. Fig. 12 is a sectional detail on the line 12 12, Fig. 2, looking toward the right, of the controlling-cam for the low-pressure abutment, showing the locking- 45 segment and the knuckle-arm support or carrier for the cam-follower to be described. Fig. 13 is an enlarged detail, partly broken off to save space, of the abutment or diaphragm which is moved into and out of the cylinder, 50 the upper end of the abutment being shown in section. Fig. 14 is a longitudinal sectional view of the abutment on the line 14 14, Fig. 13. Fig. 15 is a longitudinal sectional detail on the line 1 1, Fig. 2, through the longitudinal axis of the main shaft of the motor to show clearly the jacket-supports and jackets for both the high and low pressure cylinders, the jackets having been omitted in the preceding figures to avoid confusion. Fig. 16 is 55 an enlarged sectional detail on the line 16 16, Fig. 6, showing the packing member for one of the extensions or shoes of the low-pressure cylinder and the manner of supporting it on the extension; and Fig. 17 is an enlarged perspective detail showing the separated ends of

one of the expandible packing-rings carried by the high-pressure piston to be described in detail.

In Figs 1 and 2 I have shown the operative parts of the engine or motor as mounted upon a heavy rigid base A^x of suitable size and shape and preferably made as a casting, said base having bolted to it the various standards or other supports for the operating parts of the apparatus, and as I have shown a compound engine comprising a high and a low pressure cylinder each with its abutment and piston and the means for effecting the proper movement of the abutment I will describe such compound engine, and it will appear 75 hereinafter that the high-pressure end of the engine contains all of the essentials for a single expansion-engine. For convenience of construction the cylinders are made in four sections or parts, provided with external 80 flanges, as 3 and 4, and rigidly connected by suitable bolts, the cylinder-sections being internally grooved, so that when the said sections are assembled the high-pressure cylinder (indicated as a whole at H) will present 85 an annular piston-chamber H^x, hereinafter referred to as the "cylinder," and in which the piston travels. The flanges 3 and 4 are formed with concentric inner and outer ribs, as 3^x, (see Fig. 5,) the said ribs being machined and 90 ground to make absolutely fluid-tight joints when the cylinder-sections are assembled without requiring additional packing and reducing the amount of machining and grinding necessary. As best shown in Fig. 15, the 95 cylinder-sections are shaped to present a heavy firm bearing H' for the main shaft B^x, which extends transversely through the cylinder, its longitudinal axis forming the center of the piston-chamber proper, H^x. The outer 100 face of the bearing H' is circularly recessed at h' to form a seat for an admission-valve for the high-pressure cylinder, (shown separately 105 in Fig. 3^a,) the valve being shown as a disk V, having its hub v^x keyed to the main shaft 110 V^x and provided with a segmental slot v, Fig. 3^a. An inlet passage or conduit h² (see Fig. 1) in the lower part of the bearing H' connects the valve recess or seat h' with the inlet-port h³. (See dotted lines, Figs. 1 and 115 5.) A cover-plate h² is bolted to the bearing portion H' after the valve V is in place, completing the chamber in which the valve rotates, said cover-plate having an inlet port or conduit h⁴, registering with the outer end of the conduit h², to receive motive fluid from any suitable generator or source of supply. (Not herein shown.) The valve-disk V rotates between the opposed and adjacent ends 120 of the conduits h² h⁴, and except when the segmental admission-opening v passes between the conduits the admission of motive fluid to the cylinder is cut off. I have provided simple and efficient means for preventing 125 the escape of motive fluid at the inner end 130

of the conduit h^4 by means of rings 5 and 6, fitting easily into annular seats h^5 and h^6 in the part H' of the cylinder-casting and in the cover-plate H^2 , respectively. These rings 5 are yieldingly maintained against the opposite faces of the valve-disk by admitting the motive fluid to the annular seats h^5 and h^6 , and in Fig. 1 a small duct 6^x is shown leading into the latter seat and a duct 5^x into the seat h^6 . I have not shown any connection between these ducts and the fluid-supply, as such connection would be by piping of any suitable character. The rings 5 and 6 are annularly grooved on their inner and outer peripheries 15 to receive packing of any suitable character, which packing will bear against the inner and outer walls of the ring-seats, preventing motive fluid from creeping around the rings. By such packing device I obviate a forcible 20 wearing friction upon the opposite faces of the valve-disk, while effectually preventing leakage at the admission-conduit h^4 . The parts of the cylinder-castings which form the shaft-bearing H' are cored out, as at 7 and 25 8; Figs. 1 and 15, to prevent heating of the shaft-bearing, which might occur by reason of the jacketing of the cylinder hereinafter to be referred to.

Referring now to Fig. 15, it will be seen 30 that the opposed faces of the two upright halves of the high-pressure cylinder are separated within the piston path or chamber H^x to leave a clearance h^7 and a hub-socket h^8 for the high-pressure piston-disk and its hub, as 35 will be apparent from an inspection of Fig. 1, in which latter the piston-disk and its hub are shown in place secured to the main shaft. The piston-disk h^9 has an enlarged hub h^{10} , which is keyed in any suitable manner to the 40 main shaft, the disk being of such thickness that it will smoothly rotate in the clearance-space h^7 , and to the periphery of the disk the high-pressure piston P is rigidly secured by means to be described. The periphery of the 45 piston-disk completes the closure of the annular chamber H^x , as will be manifest; but it is necessary to pack the piston-disk in order to prevent any leakage of motive fluid from the chamber, and such packing is so arranged 50 that the friction upon the piston-disk is reduced to a minimum. Annular seats h^{11} and h^{12} are formed in the inner faces of the cylinder-sections concentric with the piston-chamber and of such radius that rings 11 and 55 12, inserted in the seats, will bear upon the opposite faces of the piston-disk near the periphery thereof. These rings are shown in position in Fig. 1, and they are yieldingly maintained in contact with the piston-disk by motive fluid at a relatively low pressure, admitted to the seats beneath the rings through ducts 11^x and 12^x , Figs. 1 and 15, these ducts terminating in nipples to which suitable pipes 60 can be attached communicating with the source of supply for the motive fluid. If the

pressure of the latter is considerable, as will be usually the case, a suitable reducing-valve of any desired or well-known construction would be introduced between the source of supply and the ducts to so reduce the fluid-pressure that the rings 11 and 12 would bear against the opposite faces of the disk h^9 with a light pressure. The rings 11 and 12, which are metallic and continuous, are grooved on their inner and outer peripheries, as shown in 70 Fig. 1, to receive suitable packing, preferably expansion or split rings, which will bear on the inner and outer walls of the seats h^{11} and h^{12} to thereby prevent the escape of the motive fluid from the piston-chamber along 75 the faces of the piston-disk. It will be manifest that a tight packing can thus be effected without exerting any undue friction upon the piston-disk, it being my object to avoid such friction wherever possible.

The high-pressure piston P is preferably a casting circular in cross-section and of such diameter that it will fit easily the chamber H^x of the cylinder. The piston is made in two longitudinally-divided halves, each half on its inner face being recessed, as at P' , (see Fig. 8,) to receive a radial extension h^{9x} of the piston-disk, and bolts 14, passed transversely through the piston and the extension h^{9x} , rigidly connect the parts of the piston to each other and to the disk. Any outward movement of the piston due to centrifugal force is counteracted by its rigid connection described with the piston-disk, and the latter, it will be remembered, is rigidly secured to the main shaft. The piston is provided with external seats or recesses p' , two of such grooves being shown, each to receive a split expansion packing-ring p^x , the separated ends of the rings coming upon opposite sides of the piston-disk. When the piston is in the annular chamber H^x , the expansibility of the rings p^x causes them to bear against the side walls of the chamber and effectually packs the piston, it being understood that the rings fit in the grooves p' fluid-tight. In Fig. 8 one ring is shown in place, and the nearer half of the other ring is cut off to show the groove for the ring and also to show a locking lug or projection p in the groove, one of these lugs being formed at each side of the piston-disk. The separated ends of the packing-ring are cut out, as at p^2 , (see Fig. 17,) to receive the lugs, the latter assisting in keeping the rings in proper position and forming abutments 100 against which the side portions of the cut-away parts p^2 bear at the separated ends of the rings to prevent leakage at such points. It will be manifest that the expansion-rings p^x will pack the piston from one to the other end of each ring; but as the rings are 105 expansible their opposed ends will not bear tightly against the faces of the piston-disk, and consequently there will be at such points a slight clearance through which the motive 110 fluid may escape. The piston is provided with a 115

fluid could pass were means not provided to prevent it. To prevent leakage at the points indicated, the opposite faces of the piston-disk are radially grooved, as at 15, Fig. 8, 5 each to receive a yielding metallic packing member p^3 , secured at its inner end by rivets 16 to the disk, its outer end extending up to the wall of the piston, and such free end of the packing member p^3 is bent up so as to project slightly beyond the face of the disk.

When the parts are in operative position, the free ends of the two packing members p^3 bear against the opposite walls of the clearance h^7 and between the packing means p^3 , effectively preventing the leakage of any fluid from one to the other end of the piston at the ends of the rings adjacent the piston-disk.

The inlet or admission port h^3 of the high-pressure cylinder is formed in the outer cylinder-half, and the outlet-port h^{30} (see Fig. 5) 20

is made in the opposite or inner half of the cylinder, so that the admission and outlet or exhaust ports are located on opposite sides of the piston-chamber or cylinder, but not 25

directly opposite each other, as will be clear from an inspection of Fig. 5. Between the 30

ports the cylinder is provided with a transverse passage intersecting the chamber H^X for the admission of an abutment which when 35

in its operative position forms the head or end of cylinder, between which and the piston the motive fluid is admitted to drive the latter in its circular path. In Fig. 15 the section is taken directly through the abutment- 40

passage, one of the faces, as 18, being shown in said figure, and the passage itself is indicated at h^{18} , Fig. 5. When a rotary engine is run at high speed, it will be manifest that the movement of the abutment out of the piston-path 45

must be effected with great rapidity, the speed of the abutment movement increasing with the speed of the engine, and one of the most important features of my present invention resides in the abutment movement and the means 50

for effecting and controlling such movement. The smaller the arc through which the piston moves during the withdrawal of the abutment from and its movement into the piston-path the greater will be the efficiency of the engine, and in my present invention the abutment 55

is moved out and in while the piston travels through an arc of forty-five degrees or during one-eighth of the entire piston-stroke. I have provided means to impart an 60

intermitting rotary movement to the abutment, and the movement is positive and exact, while the abutment is positively locked when in its operative position in the piston-path. The abutment is shown on an enlarged 65

scale in Figs. 13 and 14 and comprises a hub a and two diametrically opposite wings or extensions a' , which terminate in nearly-circular enlargements a^2 , these enlargements having accurately machined and ground faces a^3 on opposite sides to pass between the faces or

walls 18 of the abutment passage-way h^{18} in the cylinder. In the smaller figures the faces a^3 are not shown, owing to the small scale of the drawings. The outer end of each "abutment" proper, as the part a' may be termed, is arc-shaped at a' , the center of the arc being coincident with the axial center of the hub a , and an elongated recess a^4 is formed in such portion of the abutment to receive a yielding metallic shoe a^6 , secured at one end at a' in 70 the recess. When an abutment is in its operative position in the piston-path, the shoe bears against the periphery of the rotating piston-disk h^9 , and at such time the shoe acts to pack the end of the abutment and prevent 75 leakage of fluid between the abutment and the edge of the piston-disk. An annular groove a^8 is made in one face of the hub a , and such face is at the exhaust side of the abutment.

Referring to Fig. 5, the high-pressure abutment is mounted on a rotatable shaft a^9 , below and at right angles to the main shaft B^X , the shaft having a bearing in a part of a casting forming a housing or chamber in which the two connected abutments move in a circular path. The housing is made in four parts, and preferably two parts are made integral with the lower cylinder-sections. The abutment-chamber is shown at A, Figs. 1, 5, and 15, and the several parts of the casting 90

are bolted together, as at 20 21, the parts A' being integral with the cylinder-sections, while the parts A^2 are made separately and bolted together. A keyway a^{10} is formed in the abutment-hub a to receive a spline or feather a^{11} , Fig. 1, in the shaft a^9 , so that the 100

connected abutments will rotate with the shaft a^9 ; but they are permitted a slight bodily movement longitudinally of the shaft for a 105

purpose to be described. The abutment-housing opposite the annular groove a^8 in the abutment-hub is provided with an internal annular seat a^{12} , Fig. 5, to receive a coiled spring s^X , which also enters the groove a^8 , the spring normally tending to center the 110

abutment with relation to the opposite faces 115 of the passage-way h^{18} .

Supposing now that one of the abutments is in its operative position in the piston-path and that the piston has passed beyond the 120

abutment, motive fluid being admitted to the cylinder through the port h^3 between the abutment and the rear end of the piston. The pressure of the fluid acting against the abutment 125

oppositely to the force of the spring s^X forces the abutment against the face of the passage-way h^{18} on the exhaust side, and thereby absolutely seals the exhaust side of the cylinder, so that none of the fluid admitted from the inlet-port can pass the abutment. The admission of the motive fluid, it will be remembered, is governed by the opening r in the 130

disk-valve V, admission taking place so long as the opening r permits the fluid to pass from the inlet-conduit h^1 to the cylinder, cut-

off being effected as soon as the movement of the valve V has carried the inlet-opening v beyond such conduit. The motive fluid therefore operates expansively in the high-pressure cylinder or in the single cylinder of a non-compound motor, and the piston will travel through the annular cylinder in well-known manner, the exhaust fluid being discharged from the cylinder ahead of the piston through the exhaust-port h^8 . As the piston is about completing its stroke the abutment must be moved out of its path, and I have so arranged the mechanism that the abutments alternate with each other in the cylinder—that is to say, as the piston approaches the end of its stroke the abutment then in the cylinder is moved out of the piston-path at one side of the cylinder and the diametrically opposite abutment is brought into the piston-path from the opposite side of the cylinder, the piston passing the passage-way h^8 while the connected abutments are rotated through one hundred and eighty degrees. The abutment movement therefore is always in the same direction, and each movement of an abutment is through an arc of one hundred and eighty degrees, and the means by which this movement is effected will be described in detail. By employing two abutments the engine can be speeded up to a very high rate, amply sufficient time for the passage of the piston being provided during the extremely short period that both abutments are out of the cylinder. When the abutments are out of the cylinder, the imperforate portion of the valve-disk V shuts off the admission, so that there is no communication between the admission and the exhaust of the cylinder. It should be stated here that the fluid-pressure decreases from the beginning to the end of the piston-stroke, so that when it is time to move the abutment out of the cylinder the pressure on the inlet and exhaust sides thereof is substantially equalized, and therefore the force required to move the abutments does not have to overcome the pressure which acted upon the abutment during the major portion of the stroke to hold it against the exhaust side of the abutment passage-way. As soon as the pressure on the opposite sides of the abutment is equalized, and such equalization is at substantially the instant when the abutment is about to move, the spring s^8 can operate to center the abutment with reference to the side walls of the passage-way h^8 .

The abutment-chamber A is made fluid-tight, so that any leakage of the admitted fluid on the admission side of the abutment will only enter the abutment-chamber, and the amount so entering is relatively very small and in no way affects the operation of the engine.

The high-pressure cylinder is connected with the base A^8 by standards A^6 A^7 , which can be

integral with portions of the cylinder or separated therefrom, as may be most convenient or desired.

The abutment-shaft a^9 after passing through the abutment-housing is shown as provided with a bevel-pinion a^{10} , Fig. 2, in mesh with a large bevel-gear a^{11} , fast on a shaft a^{12} , supported in a bearing a^{13} on the standard A^7 . Said shaft has secured to it a transmitting member or disk a^{20} , provided with radial slots a^{21} , six of such slots being herein shown, and the portions of the disk between the slots are provided with concave locking-seats a^{22} for a purpose to be described, the slotted disk or transmitting member forming a species of star-wheel. The periphery of the disk is arranged oppositely to a locking device or segment b^8 , fast on a counter-shaft b , rotatably mounted at its ends in bearings a^{14} a^{15} , Fig. 2, the former bearing being carried by the standard A^7 , while the latter is mounted on a standard to be referred to, which partly supports the low-pressure cylinder. The counter-shaft b passes through two standards D and E , rigidly bolted to the base A^8 , and between said standards a gear B^3 is secured to the counter-shaft, said gear meshing with a second gear B^4 , fast on the main shaft B^8 between the high and low pressure cylinders, as shown in Figs. 1 and 2. The locking-segment b^8 , as shown in Figs. 9 and 10, has a circular peripheral portion which is adapted to co-operate successively with one after another of the seats a^{22} of the transmitting member during a portion of each revolution of the counter-shaft b . The remainder of the locking-segment is incurved, as at b' , to permit the partial rotation of the transmitting member, and in the construction shown herein said transmitting member makes one-sixth of a revolution for each revolution of the counter-shaft. The latter has fast upon it an elongated hub b^2 between the locking-segment and the standard D , said hub having a rigid radial arm b^3 , to which is pivotally connected at or near its outer end, as at b^4 , a swinging arm b^5 .

An actuator, shown as a pin b^6 , is extended transversely through the enlarged free end b^{50} of the swinging arm b^5 and projects at each end, as shown best in Fig. 2, the end of the actuator nearer the transmitting member being provided with a roll b^7 (see dotted lines, Fig. 2) to easily enter one of the radial slots a^{22} of the transmitting member. The opposite end of the actuator is provided with a cylindrical enlargement b^8 to co-operate with a speed-controlling device, herein shown as a cam-groove d , formed in the face of the circular head or enlargement D' of the standard D . Referring to Figs. 9, 10, and 11, the cam-groove is shown as circular for a little more than one-half its extent, and then it presents two straight portions d' , which are substantially tangent to the circular part of the groove, terminating at the high portions d^8 . Be-

tween the high portions the cam is completed by a straight part d^2 . In Fig. 11 the partly-dotted and partly-dash line indicates the path of travel of the center of the enlargement b^8 .
5 In Figs. 10 and 11 the relation of the cam-groove to the transmitting member is clearly shown.

It will be manifest that the actuator b^6 revolves bodily with the counter-shaft b , and it also has a movement toward and from such shaft, owing to the pivotal connection of the actuator-arm b^5 with the arm b^3 , which is radial to the counter-shaft. The direction of rotation of the latter is shown by the arrow 30, 15 Figs. 9 and 10, the transmitting member a^{20} turning in the opposite direction, as shown by arrow 31. In Fig. 9 the parts are shown in such position that the enlargement b^8 is in one of the tangent portions d' of the cam-groove, 20 while the roll b^7 of the actuator is just entering one of the radial slots a^{21} of the transmitting member, and it will also be seen that the next slot above is in alinement with the upper straight portion d' of the cam-groove. 25 Now as the counter-shaft b continues to revolve it will be manifest that not only will the roll b^7 travel along the slot a^{21} toward the center of the transmitting member, but it will be moved nearer to the center thereof by reason of the high portions d^x of the cam than would otherwise be the case. At the mid-portion of the advanced movement of the transmitting member, which is shown in Fig. 10, the enlargement b^8 is at the middle of the 35 straight part d^2 of the cam-groove and the roll b^7 is then nearest the center of the transmitting member, and consequently moves it with an accelerated speed. If the groove d was a continuous circle, the member a^{20} would 40 still be moved through one-sixth of a revolution for each revolution of the counter-shaft; but by shaping the cam-groove as herein shown the speed of movement of the member a^{20} is accelerated. The tangent portions d' of 45 the cam-groove permit an easy entrance and exit of the actuator from one of the radial slots of the star-wheel without any jar or bang, and as the movement of the star-wheel is about to begin the depressed portion b' of the 50 locking-disk is in such position as to permit this movement, the segment unlocking the star-wheel at the instant that its movement begins. At mid-movement the locking-segment is in the position shown in Fig. 10, and 55 as the star-wheel movement is completed the rotation of the counter-shaft causes the locking-segment to move into locking engagement with the next following locking-seat a^{22} to hold the star-wheel absolutely immovable. 60 during the remainder of the revolution of the counter-shaft the actuator carried thereby. The step-by-step or intermittent movement given to the star-wheel is transmitted through the shaft a^{18} to the bevel-gear a^{17} and from 65 it to the pinion a^{16} and the abutment-shaft a^9 ,

the parts being so proportioned that each sixth revolution of the star-wheel imparts one-half a revolution to the abutment-shaft a^9 to thereby move one abutment out of the piston-path and the other abutment into the piston-path after the piston has moved by. It has been stated that I desire to effect the abutment movement during one-eighth of the piston-stroke, and remembering this it will be manifest that the star-disk alone moving 70 one-sixth of a revolution at a time would necessitate the employment of one-sixth of the piston-stroke for the abutment movement. That would be equivalent to a clearance of thirty degrees on each side of the abutment 75 passage in the cylinder. By accelerating the speed of the star-wheel as has been described the abutment movement is speeded up, as it were, so that it will take place while the piston travels through one-eighth of its stroke, or an 80 arc of forty-five degrees. At the instant that an abutment reaches operative position in the cylinder the center of the piston is twenty-two and one-half degrees beyond it; but the actual distance or clearance between the abutment 85 and the rear end of the piston is this twenty-two and one-half degrees less the length of the piston between its center and its rear end. The admission of motive fluid into the cylinder is so regulated by the valve V that no fluid enters 90 until an abutment is in full operative position and the rear end of the piston beyond the after end of the admission-port b^2 . If the bevel-gear a^{17} has forty-eight teeth and the pinion a^{16} has sixteen teeth, it will be manifest that 95 each advance of the transmitting member a^{20} will be equivalent to eight teeth of the gear a^{17} and the pinion a^{16} will be moved through one-half of a revolution.

The counter-shaft b is rotated positively 100 from the main shaft B^X by or through the intermeshing gears B^4 B^3 , hereinbefore referred to. There is thus a constant and positive control 105 of the abutment movement from the main shaft. The faster the speed of the latter the more rapidly will the abutment movement 110 take place and always in proper timing with relation to the piston.

So far as a single engine or motor is concerned the apparatus so far described is complete, as will be obvious to those skilled in the art, and I will now describe in detail such parts of the low-pressure end of the engine as may be necessary to a full understanding 115 thereof. Before proceeding to such description, however, it should be stated that in practice the actuator b^6 is rotatably mounted in the enlargement or boss b^{50} of the swinging arm b^5 , and to reduce friction it is convenient to mount the actuator to rotate on ball-bearings, 120 and referring to Fig. 2 such ball-bearings may be located at 33 in the boss b^{50} . It will be obvious that instead of enlarging one end of the actuator, as at b^8 , and mounting a roll, 125 as b^7 , on the other end I could mount a roll 130

on each end, the object of the construction in either case being to reduce as much as possible all friction between the parts of the actuator which follow the cam-groove and coöperate with the transmitting member or star-wheel, respectively.

As with the high-pressure cylinder I prefer to make the low-pressure cylinder in sections bolted together substantially as described for the high-pressure-cylinder, and the low-pressure cylinder is indicated as a whole at L, it being provided with an annular piston-chamber L^X of greater cross-sectional diameter, however, than the high-pressure chamber H^X, this being clearly shown in Fig. 15. The main shaft B^X passes through and is supported in a lateral bearing portion L', (best shown in Fig. 15,) and the cylinder-sections are provided with annular packing-ring seats 20 l¹¹ l¹² to receive packing-rings similar to the rings hereinbefore described for the high-pressure cylinder. The bearing portion L', which is formed integral with the cylinder-sections, is recessed at l¹³, communicating with a clearance l¹⁷ to receive the hub l¹⁰ of the piston-disk l¹⁹, Fig. 4, the piston-disk being keyed or otherwise rigidly secured to the main shaft. A transverse abutment passage-way l¹⁸ intersects the piston-chamber L^X for the low-pressure abutment, and this latter is in its structure precisely like the high-pressure abutment member save that it is larger, and for that reason it needs no further detailed description, the abutment-hub being indicated in Fig. 4 at m and the diametrically opposite abutments being indicated at m². The hub is mounted to rotate with the abutment-shaft m⁹, and it is also slideable longitudinally thereof by means of a spline or feather m¹¹. On the exhaust side of the abutment-hub I have located a spring s² to center the abutment, the spring being compressed, as herein described, when the motive fluid is admitted to the low-pressure cylinder behind its piston. An abutment chamber or housing M is operatively connected with the low-pressure cylinder, said housing being made in sections, as clearly shown in Fig. 15, and connected by suitable flanges M². The housing is provided with a stuffing-box at M' for the abutment-shaft, the outer end of the latter having a bearing m^X secured to or forming part of a standard M³, which connects one side of the low-pressure cylinder with the base-plate A^X, a second standard M⁴ being provided on the opposite side of the cylinder. The general construction of the low-pressure cylinder and abutment-housing is well shown in Figs. 1 to 4, inclusive, and Fig. 15.

A bevel-pinion m¹⁶ on the abutment-shaft 60 meshes with a bevel-gear m¹⁷, fast on a shaft m¹⁸, parallel to the main shaft B^X, a bearing m²⁰ supporting the shaft m¹⁸, the latter being provided with a transmitting member or star-disk m²⁰ in all respects corresponding to the star-wheel a²⁰, hereinbefore described, oper-

ating in connection with the high-pressure cylinder.

The counter-shaft b, which it will be remembered, is supported in the bearings a²¹ a²¹, carries a locking-segment n^X similar to the segment b^X and coöperating with the locking-seats m²² of the disk m²⁰, which has radial slots m²¹ to be entered by the revolving actuator, to be described. Between the locking-segment n^X and the enlarged head E' of the stand E a hub n³ is rigidly secured to the counter-shaft b, said hub having a radial arm n³, on the free end of which is pivotally connected at n⁴ a swinging arm n⁵, enlarged at its free end to form a boss n⁵⁰.

The actuator n⁶, one end thereof being shown in dotted lines in Fig. 2, extends through the boss n⁵⁰ and is rotatably mounted therein, as described in relation to the actuator b⁶, and one end of said actuator, as n⁷, (see Fig. 12,) is cylindrically enlarged to intermittently enter and depart from one of the radial slots m²¹ of the transmitting member m²⁰. The opposite end of the actuator is provided with a roll n⁸ (see dotted lines, Fig. 2) to enter a cam-groove e in the adjacent face of the head E'. The shape of the cam-groove is clearly shown in Fig. 12, and it will be noted that it differs from the cam-groove shown in Fig. 11 in that it is circular for the greater portion of its length and then is made as a straight portion or chord connecting the ends of the circular portion. Whereas the cam device shown in Fig. 11 and for the high-pressure cylinder is an accelerating device the cam shown in Fig. 12 acts to retard the speed of angular movement of the star-wheel m²⁰, the straight portion e' of the cam-groove moving the actuator farther away from the center of the star-wheel, so that the speed of the latter is slowed down. This in connection with the low-pressure cylinder is necessary in the present embodiment of my invention owing to the greater distance between the extreme forward and rear ends of the low-pressure piston, to be described. In other respects, however, the operation of the parts between the counter-shaft b and the abutment-shaft m⁹ is similar to that hereinbefore described in connection with the high-pressure cylinder.

The admission-port for the low-pressure cylinder is shown at l³ in dotted lines, Fig. 4, because it is formed in the side of the cylinder which has been removed in such view, while two exhaust-ports l³⁰ and l³¹ are provided at opposite sides of the cylinder and offset one from the other, the port l³¹ being formed in the cylinder side wall. (Shown in Fig. 4.) The abutment-passage l¹⁸ is between the two exhaust-ports and the inlet-port l³. In Fig. 3 the inlet-port is shown in full lines, a hub or boss l³⁵, formed on the cylinder-wall, communicating therewith, and in the same figure a boss l³⁶ is shown communicating with the exhaust-port l³⁰. The exhaust-port l³¹ opens

into a boss l^37 , (see partly-dotted lines, Fig. 4,) and in actual practice the bosses l^36 l^37 would be connected by a Y-coupling communicating with the main exhaust conduit or pipe, the latter not being shown here, as it would tend to confuse the drawings and really forms no part of the invention. The motive fluid when exhausted from the high-pressure cylinder passes from the port h^{30} by means of a pipe h^{35} , (see dotted lines, Fig. 1,) and preferably in practice the exhaust would be conducted through a series of coils to be superheated before being permitted to pass through a pipe l^35 , Fig. 1, to the boss l^35 , connecting it with the admission-port l^3 .

The low-pressure piston G is cylindrical in cross-section and preferably made in two halves recessed to receive a radial extension l^3x of the piston-disk l^9 , and the extension and the two parts of the piston are rigidly held together by suitable bolts 80, Fig. 4. Packing-rings p^{15} are mounted in annular grooves in the piston and coöperate with the cylinder-walls to prevent the leakage of motive fluid, one of the grooves being shown at g' , Fig. 6, the packing-ring being broken off to show the groove. Locking-lugs g are formed on the piston to coöperate with the separable ends of the expandible packing-rings, the latter being shaped substantially as shown in Fig. 17. To prevent leakage of fluid between the upper and separated ends of the packing-rings and the piston-disk l^9 , I provide on each side of the latter a radial groove to receive a flexible metallic packing-strip g^3 , which bears against the cylinder-wall, and thereby prevents leakage at that point. I have so constructed the low-pressure piston that it serves in a manner as a valve to control the admission and exhaust ports to prevent any communication between said ports when one abutment is moving out of the cylinder and its fellow abutment is about to move into it, and to this end the piston is provided with curved and oppositely-extended extensions g^5 and g^6 . The extension g^5 is located at the leading end of the piston and the extension g^6 at its rear end, said extensions being substantially concavo-convex in cross-section and coöperating with opposite walls of the piston-chamber L^x —that is to say, the shoe or extension g^5 will act successively with relation to the exhaust-port l^{30} and the inlet-port l^3 , while the extension g^6 will act in connection with the exhaust-port l^{31} . Referring to Fig. 4, it will be seen that as the piston advances in the direction of the arrow 100 the extension g^5 will cover and close the exhaust-port l^{30} just about the time that the main body G of the piston will close the other exhaust-port l^{31} , and at this instant the abutment is moved out of the cylinder to permit the passage of the piston across the abutment-path. At that instant the inlet-port l^3 is opened, and were it not for the extension g^5 there would be established a very direct communication

through the chamber L^x between the inlet-port and the exhaust-port l^{30} , which of course would be prohibitive. Now as the piston advances the inlet-port l^3 will be closed by the extension g^5 , and the extension g^6 will act to 70 keep the port l^{31} closed until the extension has passed beyond it, the body of the piston keeping the port l^{30} closed. As the piston advances farther the rear end of the extension g^6 moves beyond the abutment-path, the inlet-port l^3 then opening as the rear end of the body of the piston passes beyond it; but at this time the incoming abutment enters and assumes its operative position in the cylinder, so that the fluid admitted through the port l^3 cannot pass 80 to the exhaust-ports because of the interposed abutment, and such fluid operates at the back of the piston to drive it forward.

To avoid machining and grinding the convex faces of the extensions g^5 and g^6 , I have 85 provided metallic packing-strips for each extension, and the packing p^{50} is shown in the drawings for the extension g^5 . This packing-strip is made substantially L-shaped in cross-section (see Fig. 16) and rests in a groove or seat g^{50} , formed in the extension, said groove having an offset recess g^{51} to receive any suitable soft packing, as p^{52} , Fig. 16, to prevent leakage around the packing member p^{50} . The latter member extends along the inner and 95 outer edges, and the end of each extension in practice abuts against the adjacent packing-ring p^{15} .

The inlet-port for the low-pressure cylinder is in continuous communication with the exhaust side of the high-pressure cylinder except at such times as the passage of the low-pressure piston closes the inlet l^3 , as has been described.

By the construction of the low-pressure piston herein shown and described I avoid the use of a separate valve to coöperate with the admission and exhaust ports at certain parts of the stroke. Were it not for the extensions the ports l^3 and l^{31} would be in communication 105 when the piston crossed the abutment-passage: but at that time the extension g^6 covers the port l^{31} and keeps it covered until the extension g^5 covers the inlet-port l^3 .

The high and low pressure pistons are set 115 opposite each other on the main shaft to balance the load, the piston-weights being equalized as much as possible. Any inequality of weight can be counterbalanced by appropriately weighting the fly-wheel W.

I have provided means between and supported by the high and low pressure cylinders to take up end thrust of the main shaft, so that there will be no longitudinal movement of the latter. Struts 102, secured to the inner end of the bearing L' , are rigidly bolted to a heavy ring-carrier L^{10} , Figs. 1 and 2, through which the shaft passes, the inner face of the ring being recessed to receive a hardened-steel bearing-ring L^{12} , Fig. 1, upon which travel 120

conical hardened antifriction-rolls 102. The hub of the gear B⁴ has secured to its adjacent end a bearing-ring L¹³, which rests upon the conical rolls 102, the heavy ring-carrier 5 L¹⁰ thereby taking up any end thrust to the left, viewing Figs. 1 and 2. On its opposite end the hub of gear B⁴ has an attached hardened ring H¹³ for a second set of conical rolls 104, and an opposing fixed ring H¹² is secured in the recessed end of a ring-carrier H¹⁰, bolted to struts 106, secured to the inner end of the bearing H', forming a part of the high-pressure cylinder H. By the end-thrust bearing last described movement of the main 10 shaft to the right is prevented, and the rolls described prevent any undue friction on the end-thrust bearing.

In Figs. 1 and 15 I have shown jackets for the cylinders, and these jackets are preferably 20 made in two parts for each cylinder. For the low-pressure cylinder the parts J and J', which may be castings, are provided with partly-circular flanges j and j' to be secured to an annular flange or face of the bearing L' 25 by screws 120 122, while the separated ends of the jacket parts are flanged at j' to be secured to the outer walls of the abutment-housing M at 123 and 124. The meeting edges of the parts J and J' overlap and are connected 30 by screws 125. Thus the low-pressure cylinder is completely inclosed by the jacket with the exception of the part of the cylinder which extends through the housing M. In practice a non-heat-conducting lining (not shown and 35 of any suitable character) may be applied to the jacket. Similar jacket members J² and J³ are applied to the high-pressure cylinder. The jackets will be placed in communication with the outlet for the waste products of combustion 40 from the generator for the motive fluid utilized in the engine, so that such hot products will keep the cylinders heated to a very high degree, thereby utilizing the waste products of combustion and increasing the efficiency 45 of the engine. By making the jackets in sections one section or part may be removed, if necessary, for cleaning without disturbing the other section, and as they are not required to withstand any pressure they can be 50 made as light castings in a convenient manner.

I have herein shown and described in detail one practical embodiment of my invention; but various changes or modifications in details of construction and arrangement may be 55 made by those skilled in the art without departing from the spirit and scope of my invention.

Having described the invention, what I claim, and desire to secure by Letters Patent, 60 is—

1. In a rotary engine, a cylinder, a rotary piston therein, an abutment movable transversely of and into the piston-path, and means to rotate intermittently the said abutment

while the piston crosses the path of the abutment. 65

2. In a rotary engine, a cylinder, a rotary piston therein, a rotatably-mounted abutment movable into and also across the piston-path, and means to rotate said abutment intermittently 70 in one direction to cause it to enter the cylinder at one side and leave it at the opposite side, the rotative movement of the abutment occurring while the piston crosses its path.

3. In a rotary engine, a cylinder, a rotary 75 piston therein, an abutment movable transversely of and into and also across the piston-path, and means independent of the piston to alternately rotate and positively lock the abutment in operative position. 80

4. The combination with an annular cylinder having oppositely-located abutment-passages, and a piston to rotate in the cylinder, of a rotatably-mounted abutment, and means to rotate it intermittently while the piston 85 crosses the path of the abutment to enter the piston-path through one of said passages, and to leave it through the other passage.

5. The combination with a cylinder, a shaft, and an attached piston to rotate in the cylinder, of an abutment to enter the cylinder into and at right angles to the piston-path, means to lock the abutment when in such position, and means to rotate the abutment when unlocked and when the piston crosses its path 95 and thereby move it out of and into the path of the piston.

6. In a rotary engine, a cylinder, a piston rotatable therein, and a shaft on which the piston is mounted, combined with an abutment 100 to close and open the piston-path, and movable at right angles thereto, and means governed by or through the shaft to intermittently rotate the abutment and to lock it when in the piston-path. 105

7. In a rotary engine, a cylinder having oppositely-located passages communicating therewith, a piston rotatable in the cylinder, an abutment movable through said passages transversely into and out of the piston-path, 110 a rotatable support on which the abutment is mounted and has a limited movement longitudinally thereof, and means to rotate said support intermittently, the pressure of the motive fluid on the abutment causing the latter to seal the cylinder behind the piston during the motive action of the fluid thereupon. 115

8. In a rotary engine, a cylinder having oppositely-located passages communicating therewith, a piston rotatable in the cylinder, 120 an abutment movable through said passages transversely into and out of the piston-path, means to rotate the abutment intermittently, the pressure of the incoming motive fluid between the piston and abutment when the latter is at rest, causing it to seal the cylinder behind the piston during the motive action of the fluid thereupon. 125

9. An annular cylinder having inlet and exhaust ports on opposite sides thereof, and a passage-way intersecting the cylinder between the ports, a piston to rotate in the cylinder, an abutment, and means to rotatably move it into and out of the piston-path at right angles thereto through the passage-way and to lock it positively when in the piston-path. 5
10. An annular cylinder having inlet and exhaust ports on opposite sides thereof, and a passage-way intersecting the cylinder between the ports, a piston to rotate in the cylinder, an abutment, a valve to govern the admission of motive fluid through the inlet-port, and an intermittently-rotated abutment movable into and out of the passage-way and having a limited lateral movement, whereby pressure of the fluid admitted to the cylinder will force the abutment against the exhaust side of the 15 passage-way. 20
11. In a rotary engine, an annular cylinder, a rotary piston therein, a plurality of abutments movable in a path transverse to and intersecting the piston-path, means to move said abutments to withdraw one from and cause another one to enter into the piston-path, such withdrawal and entrance being effected just in advance of and behind the piston, respectively, and means to hold abutments stationary 25 when either of them is in the piston-path. 30
12. In a rotary engine, an annular cylinder, a rotary piston therein, a plurality of abutments rotatably-mounted to move in a path transverse to and intersecting the piston-path, each abutment when in operative position completely closing such path, means to move rotatably and intermittently said abutments simultaneously and withdraw one from in front of the advancing piston and cause another to 35 close its path behind it, and means to hold the abutments stationary when either of them is in the piston-path. 40
13. In a rotary engine, an annular cylinder, a rotary piston therein, a plurality of rigidly-connected, rotatably-mounted abutments movable in a path at right angles to and intersecting the piston-path, means to move positively and intermittently said abutments to withdraw one from and to cause another to enter 45 the piston-path, and means to lock automatically the abutments while one of them is in position closing the piston-path. 50
14. In a rotary piston, an annular cylinder having inlet and exhaust ports on opposite sides, and a transverse abutment passage-way between them, a rotary piston in the cylinder, a plurality of rotatable abutments movable at right angles to the path of the piston into and out of the passage-way, and means to move 55 positively and intermittently, and to lock when at rest, the said abutments, the withdrawal of an abutment at one side of the passage-way and the entrance of another at the opposite side being effected just before and 60 after, respectively, the travel of the piston 65 across the passage-way. 70
15. In a rotary engine, an annular cylinder, a rotary piston therein, two oppositely-located and rotatably-mounted abutments movable in a path transverse to and intersecting the piston-path, means to lock either abutment in operative position in the cylinder, and means to intermittently rotate the abutments when unlocked through an arc of one hundred and eighty degrees to remove one from and bring 75 the other into and to close the piston-path. 80
16. In a rotary engine, an annular cylinder, a rotary piston therein, two oppositely-located and rotatably-mounted abutments movable in a path transverse to and intersecting the piston-path, means to lock either abutment in operative position in the cylinder through the major part of the piston-stroke, and means to withdraw one abutment from the path of the advancing piston and to move the other abut- 85 ment into such path behind the piston. 90
17. In a rotary engine, an annular cylinder, a rotary piston therein, two connected and diametrically opposed abutments rotatably mounted to move in a circular path into and out of the piston-path, means to move one abutment out of and the other abutment into the piston-path on each piston-stroke, and means to lock an abutment in operative position during the major part of the piston-stroke. 95
18. In a rotary engine, an annular cylinder, a shaft, an attached piston circularly movable in the cylinder, two abutments movable alternately into and out of the piston-path, and means operatively connected with and controlled by the shaft to move one abutment into and the other abutment out of the piston-path on each piston-stroke, said means including an accelerating device to effect the movement of the abutments during only a portion of each 100 revolution of the shaft. 105
19. In a rotary engine, an annular cylinder, a shaft, an attached piston circularly movable in the cylinder, two abutments movable alternately into and out of the piston-path at right angles thereto, and means to automatically move one abutment into and the other abutment out of the piston-path on each piston-stroke during a portion of each revolution of the shaft and to positively lock said abutments 110 from movement during the remainder of each shaft-revolution. 115
20. An annular cylinder for rotary engines, comprising opposed halves each having a circular groove in its inner face concentric with the piston-path, a shaft extended transversely through the cylinder and coaxial with said grooves, a piston-disk secured to the shaft and having an attached piston movable in the cylinder, an annular packing-carrier in each 120 groove, means to conduct fluid under pressure into the grooves to act upon and maintain each carrier in yielding contact with the 125

adjacent face of the disk, and packing-rings on the outer and inner peripheries of each carrier in engagement with the adjacent walls of the grooves.

5 21. In a rotary engine, a cylinder, a piston rotating therein, a shaft extended transversely through the cylinder and having an attached disk to which the piston is secured, an abutment mounted to rotate in a path transverse to and intersecting the piston-path, a yielding shoe on the outer end of the abutment to bear against the periphery of the disk when the abutment is in operative position, and means to rotate intermittently the said abutment.

15 22. In a rotary engine, a cylinder, a piston rotating therein, a shaft extended transversely through the cylinder and having an attached disk to which the piston is secured, an abutment mounted to rotate in a path transverse to and intersecting the piston-path and having an elongated recess in its end, a yielding shoe therein to bear against the periphery of the piston-disk when the abutment is in operative position, and means to rotate the abutment intermittently to withdraw it from the cylinder on the approach of the piston and to move it into the cylinder after the piston has passed.

30 23. In a rotary engine, a cylinder, a piston rotatable therein, an abutment movable in a circular path into and out of the cylinder, a continuously-revolving actuator movable toward and from its axis of revolution, a rotatable transmitting member operatively connected with the abutment and intermittently engaged and moved by the actuator, and means to move the actuator relatively to its axis of revolution when in coöperation with the transmitting member to govern the speed of the latter.

40 24. In a rotary engine, a cylinder, a piston rotatable therein, an abutment movable in a circular path into and out of the cylinder, a continuously-revolving actuator movable toward and from its axis of revolution, a rotatable transmitting member operatively connected with the abutment and intermittently engaged and moved by the actuator, means to move the actuator relatively to its axis of revolution when in coöperation with the transmitting member, to accelerate the speed of the latter, and means to positively lock said transmitting member when the actuator is not coöperating therewith.

55 25. In a rotary engine, a cylinder, a piston rotatable therein, an abutment movable in a circular path into and out of the cylinder, a continuously-revolving actuator movable toward and from its axis of revolution, a rotatable transmitting member operatively connected with the abutment and intermittently engaged and moved by the actuator, means to move the actuator relatively to its axis of revolution when in coöperation with the transmitting member, to accelerate the speed of

the latter, and a rotating locking device to coöperate with the transmitting member in alternation with the actuator, to lock said member between its successive movements.

70 26. In a rotary engine, a cylinder, a piston rotatable therein, an abutment movable in a circular path into and out of the cylinder, an actuator continuously revolving at a predetermined rate relative to the piston and movable toward and from its axis of revolution, a rotatable transmitting member operatively connected with the abutment and rotated step by step by intermitting engagement with the actuator, and means to move the latter relatively to its axis of revolution when coöperating with the transmitting member, to accelerate the speed thereof.

75 27. In a rotary engine, a cylinder, a piston rotatable therein, an abutment movable in a circular path into and out of the cylinder, a continuously-revolving actuator movable toward and from its axis of revolution, a radially-slotted, rotatable transmitting member operatively connected with the abutment and intermittently moved by the entrance into and departure of the actuator from the slots, and means to move the actuator away from its axis of revolution while coöperating with the transmitting member, to accelerate the speed of the latter.

80 28. In a rotary engine, a cylinder, a piston rotatable therein, an abutment movable in a circular path into and out of the cylinder, a continuously-revolving actuator movable toward and from its axis of revolution, a radially-slotted, rotatable transmitting member operatively connected with the abutment and intermittently moved by the entrance into and departure of the actuator from the slots, and a cam having a circular portion and symmetrical high portions, to govern the movement of the actuator relative to its axis of revolution, said actuator entering and leaving a slot of the transmitting member at the high portions when the slot is tangential to the circular portion of the cam, a straight portion of the cam between the high points governing the actuator between them.

85 29. In a rotary engine, a cylinder, a piston rotatable therein, an abutment movable in a circular path into and out of the cylinder, a continuously-revolving actuator movable toward and from its axis of revolution, a radially-slotted, rotatable transmitting member operatively connected with the abutment and intermittently moved by the entrance into and departure of the actuator from the slots, and a cam having a circular portion, and tangent portions in planes intersecting the axis of rotation of the transmitting member, the extremities of the tangent portions being connected by a straight portion, the tangent portions moving the actuator into and out of the radial slots of the transmitting member without jarring and causing the speed of said

95

member to be accelerated during the engagement therewith by the actuator.

30. In a rotary engine, a cylinder, a piston rotatable therein, an abutment movable in a circular path into and out of the cylinder, a continuously-rotating shaft having a radial arm, an actuator carried by the arm and movable toward and from said shaft in parallelism therewith, a rotatable, radially-slotted disk operatively connected with the abutment and located at one side of the path of said arm, the actuator moving into and out of a slot on each revolution of the shaft and partly rotating the disk, and a cam on the opposite side of the path of said arm and in engagement with the actuator, to govern its entrance to and exit from a slot of the disk and direct its movement during coöperation with the disk, to control the speed of angular movement of the latter.

31. In a rotary engine, a cylinder, a piston rotatable therein, an abutment movable in a circular path into and out of the cylinder, a continuously-rotating shaft having a radial arm, an actuator carried by the arm and movable toward and from said shaft in parallelism therewith, a rotatable, radially-slotted disk operatively connected with the abutment and located at one side of the path of said arm, the actuator moving into and out of a slot on each revolution of the shaft and partly rotating the disk, a cam to coöperate with the actuator and vary its radial movement when in engagement with the disk, and an intermittently-operating locking device to coöperate with the disk and hold it from movement when the actuator is disengaged therefrom.

32. In a rotary engine, a cylinder, a piston rotatable therein, an abutment movable in a circular path into and out of the cylinder, a continuously-rotating shaft having a radial arm, an actuator carried by the arm and movable toward and from said shaft in parallelism therewith, a locking-segment on the shaft, a rotatable, radially-slotted disk operatively connected with the abutment and adapted to be intermittently engaged by the actuator, said disk having peripheral concave seats between the slots to coöperate with the locking-segment, the actuator moving into and out of a slot on each revolution of the shaft, to partially rotate the disk, and a cam to coöperate with the actuator and vary its radial movement when in engagement with the disk, to control the speed of angular movement of the latter.

33. In a rotary engine, a cylinder, a main shaft extended transversely through it, a piston secured to the shaft and rotatable in the cylinder, two diametrically opposite abutments rotatably mounted and movable in a circular path into and out of the piston, a continuously-revolving actuator operatively connected with and driven by the main shaft and movable toward and from its own axis of revo-

lution, a rotatable transmitting member operatively connected with the abutments and intermittently engaged and moved by the actuator, and means to move the latter relatively to its axis of revolution when in coöperation with the transmitting member, to govern the speed of the latter, each forward movement of the transmitting member moving one abutment out of and the other abutment into the path of the piston, before and behind the latter respectively.

34. In a rotary engine, a cylinder, a main shaft extended transversely through it, a piston secured to the shaft and rotatable in the cylinder, two diametrically opposite abutments rotatably mounted and movable in a circular path into and out of the piston, a continuously-revolving actuator movable toward and from its axis of revolution and positively driven by the main shaft at a predetermined rate relatively thereto, a rotatable transmitting member operatively connected with the abutments, and intermittently engaged and moved by the actuator, means to lock said member between its intermitting movements, and a cam to move the actuator relatively to its axis of revolution when coöperating with the transmitting member, to govern the speed of the latter.

35. In a rotary engine, a cylinder, a piston rotatable therein, a main shaft extended transversely through the cylinder and to which the piston is attached, two connected and diametrically opposite abutments movable in a circular path into and out of the cylinder in the path of the piston, a counter-shaft positively driven by the main shaft, a locking-segment and an actuator mounted on said counter-shaft, the actuator being movable toward and from the counter-shaft, a radially-slotted star-wheel adapted to be intermittently engaged and moved by the actuator and provided with peripheral concave seats to successively coöperate with the locking-segment, said star-wheel being operatively connected with and adapted to rotate intermittently the abutments, and an accelerating device to coöperate with the actuator and move it radially to increase the rapidity of movement of the star-wheel when said actuator is in operative engagement therewith, each movement of the star-wheel moving one abutment out of the cylinder and the other abutment thereinto to permit the piston to travel across the abutment-path.

36. In a rotary engine, high and low pressure annular cylinders, a main shaft extended through them, pistons rotatable in the cylinders and secured to the main shaft diametrically opposite each other, a rotatable abutment for each cylinder, movable in a circular path intersecting the piston-path in each, and connections between the main shaft and each abutment to impart intermittent rotative movement thereto, to cause the said abutments to

move out of the cylinders in front of, and into the cylinders behind, their respective pistons.

37. In a rotary engine, high and low pressure annular cylinders, a main shaft extended through them, pistons rotatable in the cylinders and secured to the main shaft diametrically opposite each other, a rotatable abutment for each cylinder, movable in a circular path intersecting the piston-path in each, and means positively actuated by or through the main shaft to alternately lock and rotatably move the abutments, the movement of each abutment carrying it out of the cylinder in advance of, and causing it to enter the cylinder behind its piston, to permit the latter to cross the path of movement of the abutment.

38. In a rotary engine, high and low pressure annular cylinders provided with inlet and exhaust ports, a main shaft extending through the centers of the cylinders, pistons rotatable in the latter and secured to the shaft diametrically opposite each other, a rotatable valve controlling the admission of motive fluid to the inlet-port of the high-pressure cylinder, an abutment for each cylinder, movable in a circular path intersecting the piston-path thereof, means actuated by the main shaft to move the abutments into their cylinders at one side and from the cylinders at the opposite side, a connection between the exhaust-port of the high-pressure cylinder and the inlet of the low-pressure cylinder, and means on the piston of the latter to govern the inlet and exhaust ports of the low-pressure cylinder.

39. In a rotary engine, high and low pressure annular cylinders provided with inlet and exhaust ports, a main shaft extending through the centers of the cylinders, pistons rotatable in the latter and secured to the shaft diametrically opposite each other, a rotatable valve controlling the admission of motive fluid to the inlet-port of the high-pressure cylinder, two rotatably-mounted and diametrically opposite abutments for each cylinder, movable in a circular path intersecting the cylinder, intermittently-operating means actuated by the main shaft to move one abutment of each pair out of its cylinder in front of the piston and to move the other abutment into the cylinder after the piston has moved past, a connection between the exhaust-port of the high-pressure cylinder and the inlet-port of the low-pressure cylinder, and means to govern the inlet and exhaust ports of the low-pressure cylinder.

40. In a rotary engine, high and low pressure annular cylinders provided with inlet and exhaust ports, a main shaft extending through the centers of the cylinders, pistons rotatable in the latter and secured to the shaft diametrically opposite each other, separate means to control the inlet and exhaust ports of the two cylinders, a connection between the exhaust-port of the high-pressure cylinder and the inlet-port of the low-pressure cylinder, two diametrically opposite and rotatably-mounted

abutments to coöperate with and movable in a circular path intersecting each cylinder, means to intermittently move the pairs of abutments to move one of each pair out of the path of its piston and the other into the cylinder behind the piston, and means to lock the abutments in operative position in the cylinders.

41. In a rotary engine, high and low pressure annular cylinders provided with inlet and exhaust ports, a main shaft extending through the centers of the cylinders, pistons rotatable in the latter and secured to the shaft diametrically opposite each other, a rotatable valve controlling the admission of motive fluid to the inlet-port of the high-pressure cylinder, two rotatably-mounted and diametrically opposite abutments for each cylinder, movable in a circular path intersecting the cylinder, intermittently-operating means actuated by the main shaft to move one abutment of each pair out of its cylinder in front of the piston and to move the other abutment into the cylinder after the piston has moved past, a connection between the exhaust-port of the high-pressure cylinder and the inlet-port of the low-pressure cylinder, extensions on the low-pressure piston to govern the ports thereof at each revolution of the piston, a device to accelerate the movement of the abutments co-operating with the high-pressure piston, and means to retard the movement of the low-pressure abutments to accommodate the greater length of the low-pressure piston.

42. In a compound rotary engine, high and low pressure annular cylinders, a piston rotatable in each, packing-rings on the pistons, a valve to control the admission of motive fluid to the high-pressure cylinder, a connection between the exhaust-port thereof, and the inlet-port of the low-pressure cylinder, extensions on opposite ends of the piston thereof, to govern said ports through a part of the piston-stroke, and automatically-movable abutments movable into and out of the cylinders.

43. In a compound rotary engine, a low-pressure cylinder having inlet and exhaust ports on opposite sides and between them a transverse passage-way intersecting the piston-path, an abutment movable into and out of the passage-way, a piston rotatable in the cylinder, and extensions on opposite ends of the piston to coöperate respectively with the inlet and exhaust ports, the latter being closed when the abutment is moved out of the cylinder in front of the advancing piston, thereby preventing admitted motive fluid to pass at such time direct to the exhaust.

44. In a compound rotary engine, a low-pressure cylinder having inlet and exhaust ports on opposite walls of the piston-chamber and provided with a transverse passage-way intersecting the piston-path between the ports, an abutment movable into and out of the pas-

sage-way, a piston rotatable in the cylinder, and externally-convex extensions on the ends of the piston adapted to contact with opposite walls of the piston-chamber, the leading extension and the piston-body closing the exhaust when the abutment is withdrawn to permit the passing of the piston while the following extension prevents opening of the exhaust before the inlet has been closed by the leading extension.

45. In a rotary engine, an annular cylinder, a shaft extended through it and having a disk fast thereon, a piston rigidly secured to the disk and traveling in the cylinder, said piston having annular grooves, expansible packing-rings mounted in said grooves, the ends of the rings being notched and separated by the disk, and locking-lugs in the grooves to enter the notches and position the free ends of the rings, the latter bearing against the circular wall of the piston-chamber.

46. In a rotary engine, a piston-disk having a peripheral extension, a piston recessed to receive the extension and rigidly secured thereto, the piston having external annular grooves, expansible packing-rings seated in the grooves, the free ends of each ring receiving between them the disk extension, and auxiliary packing means on the disk to prevent

leakage of motive fluid at the ends of the pack 30 ing-rings.

47. In a rotary compound engine, a main shaft, high and low pressure annular cylinders concentric therewith, each having a transverse abutment passage-way, pistons rotatable 35 in the cylinders and secured to the shaft diametrically opposite each other, a rotatable abutment to coöperate with each cylinder, a fluid-tight casing for each abutment, the abutment passage-way communicating therewith, 40 and means actuated positively by the main shaft to intermittently move the abutments for the passage of their respective pistons, the abutments moving alternately.

48. A cylinder for rotary engines, comprising 45 four externally-flanged sections, jacket-supporting flanges on the exterior of the sections, and a separable jacket adapted to be secured to the supporting-flanges to inclose the cylinder.

In testimony whereof I have signed my name to this specification in the presence of two subscribing witnesses.

WILLIAM A. E. HENRICI.
